UNITED STATES PATENT OFFICE.

GEORGE S. CROSBY, OF BRIDGEPORT, CONNECTICUT.

DESIGN FOR A TOY MONEY-BANK.

SPECIFICATION forming part of Design No. 13,298, dated September 19, 1882.

Application filed August 11, 1882. Term of patent 3½ years.

To all whom it may concern:

Be it known that I, GEORGE S. CROSBY, a citizen of the United States of America, residing at Bridgeport, in the county of Fairfield and State of Connecticut, have invented certain new and useful Improvements in Design for Toy Money-Bank, of which the following is a specification, reference being had therein to the accompanying drawing, in which I have shown my device as illustrated by a boat mounted upon wheels.

What I claim as new, and desire to secure by Letters Patent, is—

As a design for a toy money-bank, a boat mounted upon wheels, substantially as shown. 15

In testimony whereof I affix my signature in presence of two witnesses.

GEORGE S. CROSBY.
